[57] ABSTRACT

A color sorter which sorts products delivered in single file to a photoelectric scanning head by directing acceptable products into an accept chute and diverting products which do not match the color standard for the product into a reject chute designed and shaped to deflect the rejected products into reject bins and minimize reentry of deflected products into the accept chute.

1
COLOR SORTER

BACKGROUND OF THE INVENTION

This invention relates generally to sorters and more particularly to a reject-accept chute for color sorters.

Generally, a color sorter includes a hopper to which the product to be sorted is delivered and a vibratory feeder which withdraws a product from the hopper and discharges the product on counter-rotating rollers. On the rollers, the product aligns itself into a single file and is accelerated to a high speed. At the end of the rollers, the product passes through a scanning head where it is simultaneously inspected by photoelectric devices. If the product is either darker or lighter than a pre-selected standard color, an air valve diverts the product into a reject chute. All products which match the color standard are directed to an accept chute.

Because the particles are often of irregular shape, size and weight, the path taken by rejected particles varies considerably. Although all rejected particles are deflected away from the air valve nozzle, the amount of deflection varies considerably between particles. Furthermore, their irregular shape often causes them to acquire a considerable upward or downward component of velocity as well. Because the path of rejected particles is so poorly defined, a large opening must be provided in the side of the accept chute to assure passage of all rejected particles out of the chute into the reject chute. The velocity of these particles is high at normal sorting rates, between 150 and 500 inches per second. When they strike the walls of the reject chute, they rebound with high velocity. In prior chutes, a large enough percentage of rejected products rebounded back through the opening of the accept chute into the accept chute to limit the sorting efficiency.

OBJECTS AND SUMMARY OF THE INVENTION

It is an object of the present invention to provide a color sorting apparatus having an improved accept-reject chute which minimizes bounce-back.

It is another object of the present invention to provide a color sorting apparatus including a reject-accept chute having curved side walls whereby rejected product having various trajectories is directed downwardly into the reject chute.

The foregoing and other objects of the invention are achieved by a color sorter apparatus in which the reject chute has a curved wall opposite the reject nozzle whereby the particles strike the surface of the chute at acute angles with predictable rebound paths which are directed away from the opening between the accept and reject chute through which they are deflected.

BRIEF DESCRIPTION OF THE DRAWING

FIG. 1 is a side elevational view of a color sorter in accordance with the invention.

FIG. 2 is a front elevational view of the color sorter in accordance with the invention.

FIG. 3 is a schematic diagram showing the operation of the color sorter.

FIG. 4 is an enlarged view of the accept-reject chute.

FIG. 5 is a side elevational view of the accept-reject chute.

FIG. 6 is a view taken along the line 6-6 of FIG. 5 illustrating the trajectory of rejected particles.

DESCRIPTION OF THE PREFERRED EMBODIMENT

Referring now particularly to FIGS. 1, 2 and 3, there is shown a color sorting apparatus supported by stand 11. The apparatus includes a hopper 12 adapted to receive product to be sorted, a vibratory feeder 13 which accepts the product from the hopper and delivers it to counter-rotating rollers 14. On the rollers, the product aligns itself into a single file and is accelerated under gravitational forces to high speed. At the end of the rollers, the product passes through a scanning head 16 which includes three photoelectric assemblies 17, 18 and 19, FIG. 4. These photoelectric assemblies are located at 120° intervals around the housing and include an illumination system, background plates located in field of view of the photocell assemblies and a low pressure air flushing system which continuously cleans the entire optical system. Each of the assemblies contains 20 photomultiplier tubes, lenses and slits and color filters which are collectively used to measure the amount of light reflected from the background plate and the product as it passes through the scanning head. An electronic compartment 21 contains control circuits and a 25 power supply which supplies regulated power to the illumination system, to photocells and to the control circuits. The control circuits interpret the electrical current received from the photocells and accept or reject the product under observation. In the event of reject, a reject impulse is delayed for a predetermined time giving the product time to move from the inspection position to the reject position opposite the reject nozzle 22, FIG. 4. The reject system is designed around an 30 electrically operated air valve 23 which deflects the product in its free-fall trajectory to the accept chute. The rejected product is directed into a reject bin 24 while the accepted product travels down accept chute, into an accept bin 25.

Referring now more particularly to FIGS. 4, 5 and 6, the accept-reject assembly includes an accept tube or chute 26 which is inclined downwardly to receive undeflected product in its free-fall trajectory after leaving the inspection head. The accept tube 26 includes a channel portion 27. A cover portion 28 is hinged to the reject chute by hinges 29, 31 to cooperate with the sides of the channel to form an accept tube or chute. The side wall terminates short of the upper end of the channel to leave an opening 32 opposite the reject nozzle 21. The reject chute 33 includes a sloping or inclined lower wall 34 and a downwardly sloping or inclined upper wall 35. The upper wall 35 extends upwardly to the hinged cover 28. The lower wall surface of the reject chute is angled at 45° so that rejected product strikes at an acute angle and is deflected downwardly into the reject chute rather than reflect back through the opening 32. In accordance with the present invention, the top surface of the reject chute is designed to assure that rejected particles will strike the surface at an angle of 45° more or less resulting in rebound which would direct them away from the opening 32 and downwardly into the reject chute. In the example shown, the top surface of the reject chute is a curved piece of transparent plastic. Transparency is desirable to permit observing product being rejected while adjusting the controls. The shape of the curve assures particle approach angle of 45° or less as shown

schematically in FIG. 6 where the particles are shown striking the upper curved surface and being deflected downwardly into the reject chute and away from the accept chute opening 32.

Thus, there is provided an improved color sorting apparatus in which it is assured that the particles do not reenter the accept chute.

We claim:

1. In a color sorter of the type in which products to be sorted pass in a single file past an inspection station and free fall past a rejection station where rejected product is deflected from the single file by an air blast from a nozzle, the improvement comprising an accept-reject chute having an accept portion in line with the single file of particles whereby undeflected particles travel through an accept chute and a reject chute opposite said nozzle adjacent the accept chute and extending downwardly at an angle with respect to said accept

chute, said reject chute including a curved wall opposite the reject nozzle whereby deflected products which strike said curved wall are deflected downwardly into the reject chute.

2. A color sorter as in claim 1 in which the accept chute is in the form of a tube having an opening opposite the air nozzle communicating with the reject chute whereby rejected product can be deflected out of the tube.

3. A color sorter as in claim 2 in which said reject chute has inclined upper and lower wall portions.

4. A color sorter as in claim 1 wherein said curved wall is hinged to the reject chute and forms a wall of the accept tube as well as of the reject chute.

5. A color sorter as in claim 4 wherein said curved wall is transparent.
